UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

SIGNAL.

1,214,722.

Specification of Letters Patent.

Patented Feb. 6, 1917.

Application filed November 18, 1915. Serial No. 62,247.

To all whom it may concern:

Be it known that I, WILLIAM SPARKS, a citizen of the United States of America, and resident of Jackson, in the county of Jackson, in the State of Michigan, have invented new and useful Improvements in Signals, of which the following, taken in connection with the accompanying drawings, is a full, clear, and exact description:

10. This invention relates to certain improvements in diaphragm signals of the motor-driven type.

The primary object of the invention is to provide in a signal having the driving shaft disposed parallel with the diaphragm means for varying the degree of overlap of the actuating cam and the wear-piece on the diaphragm, and to accomplish this adjustment by providing simple means for adjusting the driving shaft longitudinally of its axis.

Other objects and uses will appear from the following description, taken in connection with the accompanying drawings, in which—

25. Figure 1 is a side elevation of a signal embodying the invention herein. Fig. 2 is a vertical cross section of the same. Fig. 3 is a vertical cross section similar to Fig. 2 of a slightly modified form of supporting and inclosing means for the motor and the actuating parts. Fig. 4 illustrates a modified form of wear-piece, particularly adapted for use with the form of actuating cam herein shown.

35. The invention, as shown, comprises a resonator —1— engaged with and supported by a front case section —2—, between which case section and a rear case section —3— a suitable diaphragm —4— is supported in 40 any usual and well-known manner; the two case sections and the diaphragm are rigidly secured in proper relative position by screws —5—.

In the form shown in Figs. 1 and 2, the 45 rear case section is provided with rearwardly projecting apertured ears —6— adapted to receive between them a pair of spaced brackets —7— having pintles adapted to be journaled in the apertures in said ears —6— 50 to rotatably associate the parts.

The brackets —7— are preferably formed integral with and project upwardly from an elongated cylindrical bearing —8— for the driving shaft, said bearing terminating at 55 its lower end in a flat and preferably sub-

stantially circular plate —9— secured to one end of an electric motor —10— in any suitable manner, as by screws —11—, and preferably the plate —9— and the adjacent end of the motor have interengaged portions for 60 assisting in preventing relative movement of the parts.

The motor is of the usual construction embodying pole pieces —12—, field coils —13—, armature —14—, armature shaft —15—, 65 commutator —16—, and the usual and ordinary brushes not indicated. The rear end of the motor is closed by a removable cap —17—, in which the rear end of the armature shaft is journaled, and preferably this 70 bearing is internally threaded for the reception of an adjustable threaded screw —18— and preferably carrying a rotary ball —19— forming an adjustable end thrust bearing for the armature shaft of the motor. This 75 bearing may be held in any desired position of adjustment by the nut —20—. The motor shaft —15— extends upwardly through the bearing —8—, and at a point adjacent and between the brackets —7— is provided with 80 a suitable actuating cam —21— secured upon the upper end of the armature shaft by a nut —22— preferably seated in a recess in the upper face of the cam —21—.

The cam may be of various forms and 85 shapes within the scope of this invention so long as the actuating faces or projections thereof lie in such a position that longitudinal movement of the armature shaft —15— will vary the degree of overlap of these projections upon a wear-piece —23— rigidly secured to the diaphragm, preferably adjacent the center thereof; and in the form shown, the cam is provided with actuating projections curved in a plane traversing the 95 plane of rotation of the cam so that the projections are obliquely disposed with respect to the plane of the diaphragm, and by raising and lowering the cam through the medium of end thrust bearing —18—, the 100 degree of overlap of projections of the cam upon the wear-piece —23— may be varied, due to the fact that such movement causes the wear-piece to contact with different points along the obliquely disposed projections of the cam. Preferably the motor —10— is provided with a sheet metal cover —24— secured to its lower end for inclosing the cap —17— and bearing —18—.

In Fig. 3 the disposition of the cam and 116

wear-piece is identical with that disclosed in the former figures and the movement of the shaft —15— longitudinally of its axis accomplishes the identical adjustment heretofore described. In this illustration, however, the rear case section —3— is shaped to inclose the cam —22— and is provided with transverse apertured portions —25— and —26—, the latter being internally threaded for the reception of the externally threaded bearing —8—, and the proper rigidity of the parts is attained by locking nuts —27— and —28— positioned upon opposite sides of the portion —26—.

15 Although in Figs. 1 and 2 a certain freedom of movement exists in the armature shaft relative to the motor case, yet with the perpendicular disposition of the shaft gravity tends to hold it in contact with the 20 end thrust bearing. Further the oblique disposition of the cam teeth likewise holds the motor shaft in constant contact with the end thrust bearing —18—, due to the thrust exerted upon the cam by the wear-piece 25 —23—. In Fig. 3, however, an end thrust bearing is provided which deprives the motor shaft of any freedom of movement longitudinally of its axis, and by which the 30 motor shaft may be positively moved in either direction. In this illustration the cap —17— is provided with an internally threaded bearing for the reception of a sleeve —29—.

The inner end of the sleeve —29— is provided with an internal flange —30— forming a seat or shoulder for coöperative engagement with a stepped member —31— mounted upon the end of the armature shaft —15— adjacent the commutator —16— and 40 held in place by a suitable locking nut —32—. The rear portion of the sleeve —29— is internally threaded for the reception of set screw —33— carrying a rotary ball —34—, which ball, in like manner as 45 the ball —19—, in adjusted position of set screw —33— bears against the adjacent end of armature shaft —15— and forms an end thrust bearing therefor.

It will be readily apparent that the set 50 screw —33— may be adjusted to account for different lengths of armature shafts and for variance in the size of parts, and when the screw is properly adjusted with respect to the shaft, the sleeve —29— may be adjusted through its bearing to positively raise and lower the shaft —15—, and to 55 positively and rigidly hold said shaft in any desired position of adjustment of the cam —22— with respect to wear-piece —23—.

60 The sleeve may be provided with a locking nut —35— for assisting in holding the sleeve in any desired position of adjustment.

Although I have shown and described 65 particular constructions and methods of op-

eration as adapted for accomplishing the end in view, I do not desire to limit myself to any particular construction or any specific method of operation, as many changes may be made in the form of the parts and in the details of construction and operation of the same without departing from the spirit of this invention as set forth in the appended claims, the basic features of which resides in varying the overlap of the cam teeth upon the diaphragm wear-piece by adjusting the driving shaft longitudinally of its axis and in a direction substantially parallel with the plane of the diaphragm.

What I claim is:

1. In a signal, a diaphragm having an impulse-receiving portion, a rotary driving shaft disposed substantially parallel with the diaphragm, a rotor carried by said driving shaft, said rotor having teeth projecting radially therefrom for contact with said impulse-receiving portion, and means for moving said rotor in a direction substantially parallel with the diaphragm to vary the degree of overlap of said teeth upon said impulse-receiving portion in a direction radially of the axis of rotation of the rotor.

2. In a signal, a diaphragm having a wear-piece thereon, a motor having its armature shaft disposed substantially parallel with the diaphragm, a cam upon the motor shaft, said cam having its actuating portions disposed obliquely to the axis of rotation of the cam, and means for adjusting the armature shaft longitudinally of its axis.

3. In a signal, a diaphragm having an impulse-receiving portion, a rotary driving shaft disposed substantially parallel with the diaphragm, a rotor carried by said driving shaft, said rotor having teeth projecting radially therefrom for contact with said impulse-receiving portion, and means for moving said shaft longitudinally to vary the degree of overlap of said teeth upon said wear-piece in a direction radially of the axis of rotation of the rotor.

4. In a signal, a diaphragm having a wear-piece thereon, a rotary cam rotating in a plane substantially perpendicular to the diaphragm and having its actuating projections obliquely disposed with respect to the axis of rotation of the cam, means for rotating the cam, and means for moving the cam axially to vary the degree of overlap of the cam projections on said wear-piece.

5. In a signal, a diaphragm having a wear-piece thereon, a driving shaft disposed substantially parallel with the plane of the diaphragm, a cam mounted on said shaft for coöperative engagement with said wear-piece, said cam having its actuating projections obliquely disposed with respect to the axis of said shaft, means for moving the cam axially to vary the degree of overlap of said projections upon said wear-piece.

6. In a signal, a diaphragm having a wear-piece thereon, a rotary electric motor having its armature shaft disposed substantially parallel with the diaphragm, an actuating cam mounted upon said motor shaft and adapted for co-operative engagement with said wear-piece, said cam having its actuating projections obliquely disposed with respect to the axis of said shaft, and means for moving said shaft axially to vary the degree of overlap of the cam projections on said wear-piece. 35
7. In a signal, a diaphragm having an impulse-receiving portion, a rotary electric motor having its armature shaft disposed substantially parallel with the diaphragm, a rotor mounted on said shaft, means for positively reciprocating said shaft relatively to the body of the motor to reciprocate said rotor, the reciprocation of said rotor varying the degree of overlap of said rotor on said impulse-receiving portion. 40
8. In a signal, a diaphragm having an impulse-receiving portion, a rotary electric motor having its armature shaft disposed substantially parallel with the diaphragm, a rotor mounted on said shaft, an end thrust bearing for said shaft adapted to positively move the same longitudinally of its axis in both directions relatively to and independent of the body of the motor to reciprocate said rotor, the reciprocation of said rotor varying the degree of overlap of said rotor on said impulse-receiving portion. 45
9. In a signal, a diaphragm having an impulse-receiving portion, a rotary electric motor having a driving shaft disposed substantially parallel with the diaphragm, a rotor mounted on said shaft, an end thrust bearing for said shaft adapted to positively move the same longitudinally of its axis in both directions relatively to and independent of the body of the motor to reciprocate said rotor, the reciprocation of said rotor varying the degree of overlap of said rotor on said impulse-receiving portion. 50
10. In a cam-actuated diaphragm signal, a diaphragm having an impulse-receiving portion, a rotary cam having radial projections merging into axial projections, a pivotally carried rotary shaft upon which said cam is mounted, said shaft adapted to be moved about said pivot to bring different portions of said projections into contact with said impulse-receiving portion upon rotation of said shaft. 55

In witness whereof I have hereunto set my hand this ninth day of November, 1915.

WILLIAM SPARKS.
